U.S. Cl. D6—161

The figure is a front and right side perspective view of a work station showing our new design.

The rear of the work station consists of two plain and unornamented panels extending from side to side and separated by the open space shown between the work surface and the panel behind the shelves. The top of the lower rear panel is contiguous to the bottom of the work surface.

We claim:

The ornamental design for a work station, as shown and described.
